ATTORNEY

UNITED STATES PATENT OFFICE

HARVEY CLAYTON RENTSCHLER, OF EAST ORANGE, NEW JERSEY, ASSIGNOR TO WESTINGHOUSE LAMP COMPANY, A CORPORATION OF PENNSYLVANIA

GLOW RELAY TUBE

Application filed January 9, 1930. Serial No. 419,524.

This invention relates to an electrical discharge device of the gaseous conduction type and more particularly relates to a device in which the discharge takes place between cold electrodes in a gaseous atmosphere at a reduced pressure.

This invention is an improvement in the device disclosed in my copending application Serial No. 252,437 filed February 7, 1928 and 10 entitled Glow relay tube, from which application a divisional application Serial No. 350,164 was filed on March 27, 1929.

In the glow relay device set forth in the above identified copending applications I 15 have provided means for initiating a glow discharge by positioning a starting anode in close spaced relationship to the cathode upon which may be impressed an electrical potential sufficient to initiate a discharge between the electrodes. I also provide a main anode adjacent to the starting anode but spaced relatively further from the cathode than the starting anode upon which is impressed a lower electrical potential substantially approximating the operating potential 25 of the electrical discharge.

The glow relay device such as is disclosed and claimed in the above identified divisional application Serial No. 350,164 has been applied 30 in a number of electrical devices and systems one of which is set forth and claimed in my copending application Serial No. 328,243, filed December 24, 1928 entitled X-ray intensity meter.

In the X-ray intensity meter I pass the rays which may consist of visible light, ultraviolet light, or X-radiations into a discharge device which is sensitive to such X-radiations to cause a small electric current to flow 40 through the device, the amount of the current flow depending upon the intensity of the X-radiations.

The ray sensitive device is connected to a source of potential and to a condenser of pre-determined capacity so that after the ray sensitive device has been subjected to a definite quantity of X-radiations being investigated the condenser will acquire a definite potential. The terminals of the condenser are connected to the terminals of a gaseous conduc-

tion device having a definite breakdown potential, such as a gaseous discharge lamp or a glow relay tube. When the condenser has acquired a charge having a potential equal to the breakdown voltage of the gaseous conduction device the condenser discharges through the device and either records the discharge, operates a signal or sets mechanism into operation to terminate the source of the X-radiations.

It is highly essential in the application of X-ray, ultraviolet ray and the like radiations for medicinal purposes to definitely measure the amount of or the time of exposure of the patient thereto.

I have found that when a device of the glow relay type is employed in the specific combination of elements, as set forth in the intensity meter device of copending application Serial No. 328,243 above identified, that 70 the sensitivity of the device is materially altered through electrical leakages and that the specific structure of the device and assembly of elements therein, which are set forth in copending application Serial No. 350,164 above identified must be altered in order to eliminate such electrical leakage.

Before further disclosing the nature of my invention reference should be had to the accompanying drawing wherein,

Fig. 1 is a side elevational view of a glow discharge tube constructed in accordance with the invention set forth in copending application Serial No. 350,164 having the enclosing glass envelope broken away and the cathode shown in cross section to illustrate the constructional features of the device;

Fig. 2 is a side elevational view of the same device constructed in accordance with the present invention having the enclosing glass envelope broken away and the cathode shown in cross section.

In accordance with the present invention I have found that there is an electrical leakage between the starting or closer spaced anode of the glow relay tube and the cathode which takes place between the closely spaced leading in wires. The leakage path may lie either along the glass surfaces or through the insulating material of a common base.

member of the device. This leakage can only be eliminated by bringing the starting anode leading in support wire through the enclosing glass envelope at a point remote from the common press of the device and a common base member may not be employed.

As constructed in accordance with the invention set forth in my prior application and as set forth in Fig. 1 of the drawing attached hereto, the glow relay tube is comprised of an enclosing glass envelope 1 and a cylindrical cathode 2 of relatively large diameter, a starting anode 3 and a control anode 4, a starting tip 5 integral with cathode 2 and positioned in close spaced relationship to starting anode 3, the leading-in support wires of cathode 2, starting anode 3 and control anode 4 passing through press 6 into a base 7 from thence into pins 8. The interior surface of the cathode may be coated with a sputtered layer of an electropositive metal such as misch metal or the alkali metals.

According to the present invention the leading-in support wire 9 for the control anode 3 is removed entirely from the common press 6 of the device and is brought into the device through the enclosing glass envelope 1 at a point remote from the press 6, such as is indicated in Fig. 2.

I preferably employ a dummy support wire 10 for the control anode 3 which is extended from the press 6 and sealed therein to assist in the positioning of the anode 3. It has been found that in the course of manufacture the interior surface of the enclosing glass envelope 1 is substantially degasified and cleansed of the deleterious electrically conductive film thereon and that electrical leakage between closely spaced electrodes or support wires from this source is usually not experienced. The exterior surface of the envelope is not so cleaned and the usual electrical leakage is obtained across this exterior surface and not the interior surface. I may therefore employ a support wire in the manner herein shown but to prevent electrical leakage the leading-in wire must be brought through the envelope at a point remote from the leading-in wire to the cathode element to prevent electrical leakage through the exterior electrically conductive film usually present on glasses.

I may comprise one or both electrode tips 3 and 4 of a highly reactive rare refractory metal such as thorium, titanium, uranium and the like, which metals have the property of reducing the potential required to initiate an electrical discharge between the anode electrode and cathode. A gas pressure of an inert gas such as argon at from 5 to 8 millimeters mercury pressure may be employed, the specific pressure employed depending in part upon the particular gas and the electrode spacing employed.

With thorium electrodes and from 5 to

8 m. m. mercury and argon gas pressure in the device, a spacing of about 1.0 m. m. is preferred between the cathode starting tip 5 and starting anode 3. With this specific arrangement of elements the electrical leakage of the charge accumulating in the condenser of the ray intensity meter device of the above identified copending application Serial No. 328,243 through and across the glass of the press of the device or between the leading-in wires through the base member thereof, is substantially eliminated and the reliability and accuracy of the intensity meter device incorporating the same materially increased.

Having broadly and specifically set forth the nature of the present invention it is apparent that there may be many variations made of the specific embodiment herein disclosed without departing from the nature of the invention and such variations and modifications are anticipated as may fall within the scope of the accompanying claims.

What is claimed is:

1. A glow discharge device comprising an envelope, a cathode of large area within said envelope, a starting anode of smaller area than said cathode and closely spaced therefrom, and a main anode adjacent said cathode but spaced a greater distance therefrom than said starting anode, leading-in wires for said cathode, starting anode and main anode, the leading-in conductor for said cathode being sealed into the envelope at a point opposite the position where the leading-in conductor for the starting anode is sealed whereby electrical leakage between the leading-in conductors for said cathode and starting anode is prevented.

2. A glow relay device comprising an envelope having a press, a cathode of relatively large area, a main anode spaced from said cathode and a starting anode also spaced from said cathode, the distance between said starting anode and said cathode being less than the distance between the main anode and the cathode, a plurality of lead in wires connected to said anode and said cathode, sealed in said press and extending outside the lower portion of said envelope, a support wire sealed to said press and to said envelope at a point remote from said press, said support wire supporting said starting anode and being in electrical connection therewith.

In testimony whereof, I have hereunto subscribed my name this 7th day of January, 1930.

HARVEY CLAYTON RENTSCHLER.
